TOOTHED WHEEL PUMP

Filed Sept. 21, 1931

FIG : 1. Inventor
William Drysdale.

By William C. Linton.
Attorney.

UNITED STATES PATENT OFFICE

WILLIAM DRYSDALE, OF YOKER, GLASGOW, SCOTLAND, ASSIGNOR TO DRYSDALE AND COMPANY, LIMITED, OF GLASGOW, SCOTLAND

TOOTHED-WHEEL PUMP

Application filed September 21, 1931, Serial No. 564,108, and in Great Britain October 31, 1930.

This invention relates to toothed-wheel pumps. The object is to provide a pump well adapted for supplying a small quantity of liquid at a high pressure. For such a duty 5 the ordinary type of single-stage toothed-wheel pump is not suitable owing to the leakage losses which occur with high pressures. According to the present invention the fluid is raised in pressure in two stages, that is by 10 toothed wheels in series; and a construction is employed which will be described in the following specification. The invention will be defined in the annexed claims.

The accompanying drawing illustrates the 15 carrying of the invention into effect.

Fig. 1 is a sectional elevation of a pump driven by an electric motor and constructed according to the invention. (The motor is not in section.)

20 Fig. 2 is a section on the line AA of Fig. 1.

A main casing *a* is provided: This is of a nature suitable for supporting the driving motor which in the present case is an electric motor *b*. Through the main casing passes the 25 driving shaft *c* of the pump: This shaft is driven from the motor by a chain *d* running on sprocket wheels *e* and *f* on the motor shaft and pump shaft respectively.

Bolted to one end wall *a'* of the main casing is a casing *h* which will be termed the enveloping casing. It is dome-shaped; it encloses the pump proper.

The pump proper consists of two sets of intermeshing toothed wheels. One set,—viz. 35 *m*, *n*—constitutes a low-pressure pump: the other set,—viz. *r*, *s*—constitutes a high-pressure pump. One wheel of each of the two stages,—viz. the wheels *m*, *r*—are mounted on the driving shaft *c*. The other wheels, viz. 40 *n*, *s*, are mounted on a shaft *o* which is not driven except by the intermeshing of the pump wheels. All the wheels are contained in an annular wheel-case *t* of I-section having an apertured web. This wheel-case is 45 enclosed in the enveloping casing *h* with its inner end face abutting the end wall *a'*. The two shafts *c*, *o* traverse the apertures in the web of the wheel-case and are journalled at their outer ends in bearings *u*, *v* formed in 50 a casting *w* which is spigoted at *x* within the

enveloping casing *h*, said casting *w* forming a cover for the outer end face of the wheel case *t*. Inner bearings 2, 3 for the two shafts are provided in the main casing.

The suction inlet 4 and the discharge outlet 55 5 are formed in the main casing and are located above the pump proper. The latter therefore remains always charged with liquid even although the said inlet and/or outlet are opened; and moreover this arrangement ensures that, when starting the pump, the latter being full of liquid, a powerful initial suction effect can be obtained.

The toothed wheels *m*, *n*, *r*, *s*, may have ordinary straight parallel teeth or they may 35 be of the single-spiral type: In the latter case the high-pressure wheel on each shaft is arranged with opposite direction spiral to that on the low-pressure wheel on the same shaft with a view to balancing end thrust.

A stuffing box 6 is provided on the driving shaft *c* inside the main casing. Owing to the location of the high-pressure and low-pressure pumps, the latter being next the stuffing box, leakage is reduced to a minimum.

In order however further to ensure freedom from, or reduce, leakage, a balance duct 7 is taken from the annular space 8 around the driving shaft between the stuffing box 6 and the low-pressure pump and is led to the 80 suction chamber 9 of the pump. A controlled leak-off device 10—not of novel construction—is provided on this balance pipe.

Owing to the arrangement of the enveloping casing *h* there is only one joint to be 85 broken in order to open up the pump for inspection, that is, the joint between the enveloping casing and the main casing *a*. This fact is of importance from the points of view of convenience, saving of labour, and reduction of leakage.

The wheel case *t* is held in place as shown between the main casing *a* and the casting *w*. It, the wheel case, is not a structural part of the machine, and it can therefore be formed 95 of very hard metal—an important fact from the point of view of wear.

Various deviations in construction from that described could be employed within the scope of the invention. For example the 100

drive from the motor shaft to the shaft *c* might be by gear wheels instead of a chain; and a motor other than an electric motor might be employed.

5 It is an advantage of the present invention that, owing to the division of the work into two stages, the load on the teeth of each wheel is very much less than—approximately only half of—that of a single-stage pump 10 of equal toothed-wheel form. The wear and tear on the rotors is thus greatly reduced—a point of considerable importance.

A pump according to the present invention is specially adapted for dealing with 15 fuel oil for discharging through burners. It is however applicable in, in general, all cases where the quantity of liquid is small and the pressure high.

Having thus described my invention, what 20 I claim as new and desire to secure by Letters Patent is:—

1. A two-stage pump comprising a main casing, a driving motor resting on said main casing, a dome-shaped casing removably secured to one end wall of said main casing, an annular wheel-case of I-section having an apertured web and supported inside said dome-shaped casing with its inner end face abutting against said end wall, a pair of co-acting wheels forming a low-pressure pump 25 carried by said wheel-case on the inner side of said web, a pair of co-acting wheels forming a high-pressure pump in series with the first pump and carried by said wheel-case on the outer side of said web, shafts traversing the web apertures, one shaft passing through said main casing and carrying one wheel of the low-pressure pump and one wheel of the high-pressure pump, and the other shaft carrying the other wheel of each 30 pump and being idle, means whereby the first-mentioned shaft is driven by said motor, a casting covering the outer end face of said wheel-case, inner bearings for said shafts within said main casing, and outer bearings for said shafts within said casting.

35 40 45

the other wheel of each pump, means whereby the first mentioned shaft is driven by said motor, inner bearings for said shafts within said main casing, a cover applied to the outer end face of said wheel-case and supporting the outer ends of said shafts, a stuffing box on said first mentioned shaft within said main casing, there being an annular space between said stuffing box and the low pressure pump, and a balance duct connecting said annular space with the suction side of the pump.

70 75 80 85 90 95 100 105 110 115 120 125 130

3. A two-stage pump comprising a main casing, a driving motor resting on said main casing, a domed casing bolted to one end wall of said main casing, an annular wheel-case of I-section having an apertured web and supported inside said domed casing with its inner end face abutting against said end wall, a pair of co-acting wheels forming a low-pressure pump carried by said wheel-case on the inner side of said web, a pair of co-acting wheels forming a high-pressure pump in series with the first pump and carried by said wheel-case on the outer side of said web, shafts traversing the web apertures, one shaft passing through said main casing and carrying one wheel of the low-pressure pump and one wheel of the high-pressure pump, and the other shaft carrying the other wheel of each pump and being idle, means whereby the first-mentioned shaft is driven by said motor, a casting covering the outer end face of said wheel-case, inner bearings for said shafts within said main casing, and outer bearings for said shafts within said casting.

I hereby sign my name to this specification.

WILLIAM DRYSDALE.
